UNITED STATES PATENT OFFICE.

WILLIAM F. GROENE, OF CINCINNATI, OHIO, ASSIGNOR TO THE R. K. LE BLOND
MACHINE TOOL COMPANY, OF CINCINNATI, OHIO, A CORPORATION OF OHIO.

WORK SUPPORT.

1,405,206.

Specification of Letters Patent. Patented Jan. 31, 1922.

Application filed May 13, 1920. Serial No. 381,094.

To all whom it may concern:

Be it known that I, WILLIAM F. GROENE, a citizen of the United States of America, and resident of Cincinnati, in the county of 5 Hamilton and State of Ohio, have invented a new and useful Improvement in Work Supports, of which the following is a specification.

An object of my invention is to provide 10 means whereby fine adjustments of the support may be obtained. Another object is to provide a support that can be easily and speedily thrown in or out of position. Another object is to provide an adjustable 15 support that will not offer lodgment to dirt and permit its accumulation therein. Another object is to provide a support in which there will be no longitudinal play.

These and other objects are attained by the 20 means described herein and disclosed in the accompanying drawings in which:

Fig. 1 is an end view of a lathe bed, carriage and work support embodying my invention, parts of the support being in section.

Fig. 2 is a front elevation of a support embodying my invention, the tool rest being removed.

Fig. 3 is a sectional view on irregular line 30 3—3 of Fig. 1.

Fig. 4 is a sectional view on line 4—4 of Fig. 1.

My invention comprises a rest A, having arms a pivotally attached to the carriage C. 35 The rest is adjustably mounted on a slide B. The rest and slide are moved about the pivotal connections by means of a crank shaft E to which the slide is pivoted. The crank shaft is operated by means of the bevel gears e¹ and e² operated by the shaft e³ and crank e⁴. Rollers a⁵ and d² on the rest A and block or thrust member D engage and support the work and may be thrown in and out of engagement with the work by the manipulation 40 of the crank e⁴.

The rest A has, at its lower end, the arms a, pivotally attached to the carriage C by means of pivots a¹. On the rear of the rest is formed a longitudinal way a² in which the 50 slide B is mounted. The slide B and rest A are adapted to be securely attached to one another by means of bolts a⁹ and a¹⁰ extending transversely through the upper and lower ends of rest A and through slots in the slide B. The bolts a⁹ and a¹⁰ have nuts

a¹¹ and a¹² respectively. On the rear of the rest is a nut a¹³ that is engaged by a bolt b⁶ attached to the slide; (see Fig. 3). On the front of the rest is formed a flange a³. Secured to the flange are plates a⁶ and a⁷ and 60 rotatably mounted between them, and extending forwardly beyond them is a roller a⁵. Near the upper front edge of the flange is formed a way a⁴, (see Fig. 1) in which the block D is mounted. The block D is engaged at its upper end by the screw bolt a⁸ extending through the rest A.

The slide B is adapted to be retained within the way a² and to be reciprocated longitudinally therein. The slide B is, at 70 its lower end pivoted by stud b to link b¹. A cap b² secured to link b¹ embraces stud e of crank shaft E. A pivot b⁹ on the lower end of the slide is engaged by the bolt f¹. Lubrication of stud b is made by the duct b¹⁰. 75 Longitudinal slots b³ and b⁴ are formed through the slide through which the bolts a⁹ and a¹⁰ respectively extend. A hole b⁵ in the slide accommodates the threaded nut a¹³. A screw b⁶ extends through the slide 80 from its upper edge b⁷ to and into the hole b⁵ where it engages the threaded nut a¹³. A collar b⁸ secured to the screw b⁶ permits the screw's rotation but prevents its separation from the slide B.

The block D is adapted to be reciprocated longitudinally in the way a⁴ by means of the screw a⁸ engaging in the end of the block. A collar a¹⁴ secured to the screw a⁸ permits the screw to move the block without 90 dislodging the screw. The screw bolt d¹ extending through the longitudinal slot d¹ in the block engages in the rest A. A roller d² is rotatably secured between the jaws d³ and d⁴ formed on the block D.

The crank shaft E is mounted in block F supported on the bracket G. The stud e engages the slide B. A bevel gear e¹ mounted on the crank shaft is engaged by the bevel gear e² carried by shaft e³. The crank e⁴ 100 is attached to shaft e³. Housing e⁵ covers bevel gear e¹.

Block F is bolted to the carriage C. A tapered flat gib f is attached to the base of the block and moves over the bracket G with 105 the block and carriage. The bolt f¹ is pivotally attached at one end to the slide B by the pivot b⁹. At its other end the bolt f is screw threaded, this threaded section passing through a hole f² in the block F. The 110

lower end of hole f^2 is tapered. A self aligning tapering collar f^3 seats upon the lower end of the hole f^2 . Lock nuts f^4 and f^5 permit variation of the positions of collar f^3 . The bracket G, bolted to the lathe bed, supports the block F and gib f.

Work H (Fig. 1) is held between the head and tail stock of the lathe. h is the cutting tool held in tool rest h¹ on the carriage C.

10 The operation of the device is as follows:

After the device has been adjusted for work of a certain character, it is in condition for use on all of this work. The rest A together with block D are revolved about 15 the pivots a^1 throwing the rollers a^5 and d^2 into or out of engagement with the work by a few turns of the crank e^4 . The crank e^4 revolves the crank shaft E that moves the slide B up or down, thereby turning the rest 20 A about pivots a^1 . The bolt f^1 operates upon the rest in a manner that will be explained thre้าter.

I will now describe the method employed in adjusting the device preparatory to proceeding with a lot of work of a certain character.

The work H is secured in the lathe between the head and tail stocks. The cutting tool h is moved up to engage the work. By 30 means of crank e^4 and the bevel gear e^2 the bevel gear e^1 together with the crank shaft E are revolved, thereby moving the slide in way a^2 . As the slide moves it rotates the rest A about the stud a^1 . The rest is rotated so 35 that the roller a^5 engages the work H. The nuts a^{11} and a^{12} are loosened and by means of screw b^6 engaging in nut a^{13} the rest is adjusted so that the roller a^5 engages the work at a point opposite to the cutting tool. 40 The nuts a^{11} and a^{12} are then tightened thereby bolting rest A and slide B together. The lock nuts f^4 and f^5 are then adjusted so as to seat the collar f^3 in the tapered hole f^2 and take up any play between the slide and 45 crank shaft. Bolt d is then loosened and by means of screw a^8 , the block D is moved toward the work until roller d^2 engages the work. The bolt d is then tightened and thrust member D bolted to rest A. From 50 this description it is apparent that the rollers can be moved to various contacts with the work, supporting the work at various points in relation to the cutting tool. The device moves with the carriage, thereby giving support at these relative points at all times. By 55 means of tapered gib f, any play between the block F and bracket G can be taken up. The thrust of the cutting tool is thereby directed against the bed of the lathe. The support 60 is adjusted for a lot of work, and then is utilized in the manner previously explained. The crank e^4 is turned in a clockwise direction to move the rest A into engagement with the work H. The bolt f^1 limits the extent to which the rest can move toward the 65

work, thereby assuring the same relation between the parts of the device and the piece of work, and also binds the link B¹ and crank shaft E, when the force of the thrust of the cutting tool, operating upon the stud 70 b and tending to move the rest backward, tends to further move the link b^1 and crank-shaft E in a clockwise direction. In practice this binding force has been found to be so great that the adjustable lug f^6 was placed 75 upon the block F and the boss e^6 upon the bevel gear e^1 to further resist the clockwise tendency of the link b^1 and crankshaft E, due to the thrust of the tool. The slot f^7 in the block F permits adjustment of the lug f^6 . 80

Having thus described my invention, what I claim is:—

1. In an adjustable work support for lathes, the combination with a rest adapted to adjustably engage the work, of a slide 85 pivotally mounted on the carriage engaging the rest and adapted to control the rest, and mechanism for operating the slide, adapted to be moved along the work in unison with the carriage. 90

2. In an adjustable work support for lathes the combination with a rest, pivots connecting the rest to the carriage, a way formed in the rest, and a roller mounted on the rest, adapted to engage the work, of an 95 adjustable block having a roller adapted to engage the work, a slide engaging in the way in the rest, means to adjust the rest on the slide, a bracket mounted on the bed, a block mounted on the bracket, a crank shaft 100 supported by the block and engaging the slide and being adapted to rotate the slide and rest about the pivots connecting the rest and the carriage, and means to revolve the crank shaft. 105

3. In an adjustable work support for lathes the combination of a slide, a crank shaft pivotally connected with the slide, a bracket attached to the bed, a block slidably mounted on the bracket and supporting the 110 crank shaft, means to rotate the crank shaft, means to limit such rotation of the crank shaft, a rest pivotally attached to the carriage and adjustably engaging the slide, a block adjustably engaging the rest and rollers on the block and the rest adapted to engage the work. 115

4. In an adjustable work support for lathes, the combination of a slide, a crank shaft, a link engaging the crank shaft, a 120 pivot connecting the link and the slide, a bracket attached to the bed, a block slidably mounted on the bracket, and supporting the crank shaft, means adjustably adapted to take up play between the block and the bracket, means to rotate the crank shaft, means adapted to limit the rotation of the crank shaft, a rest pivotally attached to the carriage and adjustably engaging the slide, means adapted to secure the slide and the 125 130

- rest in fixed relation, a block adjustably mounted on the rest, means to fixedly secure the block to the rest, and rollers on the block and the rest adapted to engage the work.
- 5 5. In an adjustable work support for lathes the combination of a bracket attached to the bed, a block, having a bore forming a seat, slidably mounted on the bracket, a crank shaft mounted on the block, a gear on the crank shaft, a crank, a shaft attached to the crank, a gear on the shaft engaging the gear on the crank shaft, a slide pivotally connected with the crank shaft, a bolt pivotally attached to the slide and extending 10 through the bore in the block, a self aligning collar mounted on the bolt adapted to engage in the seat on the block, means adapted to permit adjustment of the collar, and a rest pivotally mounted on the carriage and 15 engaging the slide.
6. In an adjustable work support for lathes, the combination of a bracket mounted on the bed, a block slidably mounted on the bracket, a crank shaft mounted on the block, 20 a link engaging the crank shaft, a slide pivotally attached to the crank shaft, a rest having a way formed in it adapted to accommodate the slide and to permit the slide to reciprocate therein and comprising arms, 25 pivots connecting the arms to the carriage, means to lock the rest to the slide, and a roller adapted to engage the work, and a block adjustably mounted on the rest having a bearing adapted to engage the work.
- 30 7. In an adjustable work support for lathes, the combination with a rest adapted to engage the work, of a block, a crank shaft
- mounted on the block, a link mounted on the crank shaft, a pivot connecting the link to the rest, means to revolve the crank shaft 40 and to move the rest into engagement with the work, and an adjustable bolt adapted to bind the rest to the block thereby preventing continued rotation of the crank shaft due to the thrust upon the link and the pivot. 45
8. In a work support for lathes the combination of a rest pivotally mounted on the carriage adapted to engage the work, a slide pivotally mounted on the carriage controlling the rest, and means to control the slide. 50
9. In a work support for lathes the combination of a rest pivotally mounted on the lathe adapted to engage the work, a slide pivotally mounted on the lathe controlling the rest, and means to move the rest and 55 slide about their pivotal mountings whereby the rest is moved in and out of engagement with the work.
10. In a work support for lathes the combination of a rest adapted to engage the work, 60 a slide engaging the rest and being capable of movement longitudinal of itself, a pivot mounting one end of the slide upon the lathe, a second pivot spaced from the first mentioned pivot and mounting the rest upon 65 the lathe, means to actuate the slide about its pivotal mounting, whereby the slide is moved longitudinally over the rest, thereby moving the rest into and from engagement with the work, and means controlling the 70 movement of the slide.

In witness whereof, I have hereunto subscribed my name this 8th day of May, 1920.

WILLIAM F. GROENE.
